(57) **CLAIM**

The ornamental design for a multiple pour pitcher, as shown and described.

DESCRIPTION

FIG. 1 is a perspective view of a multiple pour pitcher embodying the new design;

FIG. 2 is an enlarged, fragmentary view thereof;

FIG. 3 is a top plan view thereof;

FIG. 4 is an enlarged, fragmentary view of the multiple pour pitcher of FIG. 1 shown in an alternative environment with an unclaimed, detachable handle; and,

FIG. 5 is a reduced scale exploded view of the multiple pour pitcher of FIG. 1, shown in an alternative environment with unclaimed environmental subject matter.

The broken lines represent unclaimed environmental subject matter.
